CLAIM

We claim the ornamental design for portions of a clamp bracket assembly for use with push button latch and lock operating assemblies, as shown and described.

DESCRIPTION

FIG. 1 is a perspective view showing principally top and front features of portions of a clamp bracket assembly for use with push button latch and lock operating assemblies embodying our new design;

FIG. 2 is a perspective view showing principally bottom and rear features thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is a perspective view showing principally bottom and front portions thereof, with broken lines disclosing the position of a push button latch and lock operating assembly clamped by the clamp bracket assembly, with this broken line disclosure being provided for illustrative purposes only and forming no part of the design.
